UNITED STATES PATENT OFFICE.

JAMES D. GIBBS, OF LOUISVILLE, KENTUCKY, ASSIGNOR TO GIBBS-INMAN COMPANY, OF LOUISVILLE, KENTUCKY.

TICKET-CUTTER.

1,326,152.

Specification of Letters Patent. Patented Dec. 23, 1919.

Application filed March 3, 1919. Serial No. 280,382.

To all whom it may concern:

Be it known that I, JAMES D. GIBBS, a citizen of the United States, residing at Louisville, in the county of Jefferson and 5 State of Kentucky, have invented new and useful Improvements in Ticket-Cutters, of which the following is a specification.

My invention relates primarily to the class of railroad tickets known as conductor's 10 cash fare receipts and more especially to the form of receipt having figures representing dollars and cents arranged in contiguous columns and having the paper scored or slotted between the columns as set forth in 15 the accompanying drawing, which fully illustrates my invention both in its normal position upon the tickets and removed from the same.

Heretofore it has been the practice to attach a straight-edge to the end of a flexible 20 cover forming a part of the binding of the tickets, and this straight-edge was designed to be manipulated by bending the cover and moving the cutting edge thereof to the desired position upon the face of the ticket; but this method has proved tedious and unsatisfactory.

Another plan has been to use a straight-edge of metal or other hard substance, holding 25 it in position by means of a rubber band, which method, however, has been found impracticable or undesirable for the reason that the bands cannot be relied upon to hold the straight-edge in the approved position 30 and, furthermore, the unavoidable friction of the bands against the sides of the book makes it necessary to constantly replace them.

These objections are obviated by the use 35 of my invention. In the drawing Figure 1 is a plan view of the sliding cutter in normal position upon the ticket book. Fig. 2 is a perspective view of the cutter complete, removed from the tickets. Fig. 3 is a 40 side view of the cutter attached to a book of tickets, and Fig. 4 is a ticket after having been severed to represent a given fare.

My invention consists of two trips of 45 sheet metal or other hard substance, which I describe as the upper or primary slide A, the lower, or secondary slide B and the connecting wires or springs c, c.

In order to maintain a proper position of the cutter upon the ticket book I bend at right angles downwardly the ends d. d. 55 of the upper slide and upwardly the ends e. e. of the lower slide, and since it is desirable that the inner surfaces of the sliding cutters and guides be smooth and adapted to slide freely upon the ticket I raise upon 60 the outer surfaces small housings, f. f. f. f. adapted to receive the ends of the connecting wires c. c., although obviously the same effect may be secured by other means.

Preferably I use wire of suitable spring 65 quality for the means of connecting the two slides; however, other means may be employed. By the use of spring wire, a yielding pressure is imparted to the upper slide, which, being swivelly connected, lies flat 70 upon the ticket, automatically adjusting itself to any thickness.

As a further convenience I form in the center of the upper slide a circular depression g, which serves as a thumb-hold for the 75 operator, and in order to prevent binding or undue friction of the lower slide while pressure is being exerted upon the upper slide I place the lower slide a short distance behind the upper slide, which arrangement 80 also secures greater accuracy of the guides.

In operation, the cutter is moved up or down until the desired figure in the first column on the ticket appears just above the upper slide; the ticket is then torn or separated along the edge of the slide as far as the first slot in the ticket, after which the second and third columns are similarly severed, the receipt or detached portion being delivered to the person paying fare and the 90 stub portion remaining in the binding until the conductor desires to remove it.

Having thus described my invention, what I claim is:

A sliding ticket cutter comprising an upper and a lower portion flexibly connected, the upper portion having downwardly turned end guides and the lower portion having upwardly turned end guides, substantially as and for the purpose described. 100

JAMES D. GIBBS.
